UNITED STATES PATENT OFFICE.

GEORGE EVANS WEBB, OF MILWAUKEE, WISCONSIN, ASSIGNOR TO KOEHRING COMPANY, OF MILWAUKEE, WISCONSIN, A CORPORATION OF WISCONSIN.

LOADING-SKIP-OPERATING MECHANISM.

Application filed March 15, 1926. Serial No. 94,824.

This invention has to do with mechanical instrumentalities for raising and lowering heavy bodies. According to the adaptation wherein I have embodied the invention as 5 presented hereinafter, a loading skip for concrete mixers is designed to be operated to hoist a load of concrete aggregates and charge the same into a concrete mixer.

To illustrate the advantages of the invention in practise, in its special adaptation to which I have referred, I note that large concrete mixing machines at the present time are supplied with the aggregates to be mixed by a skip which is pivoted at one end to the 10 frame of the machine and elevated to an inclined dumping position by means of cables and operating drums connected therewith, the cables leading to the outer or free end of the skip at which it is loaded. 15 This construction of loading skip and hoisting means possesses serious disadvantages from certain viewpoints in that in order to raise the skip to its discharging position, the frame of the machine on which 20 it is mounted must be constructed with a relatively high superstructure on which the cable hoisting drums are mounted, suitable driving means leading to said drums. The high superstructure type of mixing machine 25 offers difficulties in being transported from place to place as it will not pass under low bridges, or the like, and must needs be "knocked down" or folded temporarily, in order to transport it under certain conditions. 30

In the carrying out of my invention, I have designed loading skip operating means that does away entirely with the superstructure mounted hoisting devices, such as 35 cables, drums, etc., and eliminates the need for employing brakes and special clutches for controlling the ascent and descent of the heavy body of the skip, together with the load therein, the hoisting of which must be controlled.

To the end above set forth, I employ special lever lifting devices adapted to be mounted upon the lower part of the main machine frame to elevate the skip by lifting

forces applied from below, as distinguished 50 from the use of the high hoisting cables, connected with the skip from above.

As a special feature associated with the said lifting devices, I utilize gear mechanism by which the lifting forces are automatically varied as regards the ratio of power efficiency so that the movement of the skip will be relatively slow at maximum power when the lifted load is greatest, the speed of action of the lifting devices being 60 accelerated when the load has been moved to a point where reduced power is effective for its movement.

Another feature of novelty is the combination of a known design of variable speed 65 and reverse direction hydraulic transmission provided between the source of power and the lifting devices, and affording a very flexible operating construction to control the up and down movements of the skip or body 70 which is being hoisted and lowered at different speeds and high operating efficiency.

Still another important feature of the invention resides in the provision of automatic control devices for governing the action of the hydraulic transmission, means directing the movements of the skip, whereby the skip may at any time be stopped in its movement either upwards or downwards, whereby, when the skip reaches its discharging 80 position which is the limit of its upward movement, it will be automatically stopped, whereby a similar automatic stoppage will occur when the skip reaches the lower limit of its movement at the grade where it is 85 charged, and whereby in the event of sudden stoppage of the skip by meeting an obstruction in its downward path of movement and automatic shutting off of the driving power applied thereto will occur reducing 90 possibility of damage to the skip or breakage of any of the operating parts.

The invention includes other detail features of construction that will be more fully understood by referring to the following 95 description in conjunction with the accompanying drawings, in which:—

Figure 1 is a side elevation, somewhat

diagrammatic illustration of a concrete mixing machine, and showing the loading skip operating means of the invention, the worm gear casing being illustrated in section.

Figure 2 is a showing of the arrangement of the control levers and connections when the loading skip is in its uppermost discharging position, the full lines of the illustration showing the mechanism just before it reaches the neutralizing position, and the dotted lines indicating the arrangement of the parts after the mechanism has reached the said neutralizing position.

Figure 3 is a view similar to Figure 2 wherein the full lines show the skip just as it reaches the subgrade, and dotted lines the position of the parts depicting the additional movement of the skip raising arms after the skip reaches the subgrade, to neutralize or discontinue the operation of the oil gear.

Figure 4 is a fragmentary view showing more fully by full and dotted lines the movement of the lifting levers and relative movement of the lifting arms and points of connection thereof with the skip.

Referring to the drawings, 1 denotes the frame work of the mixing machine which may be stationary or portable, being illustrated as carried by traction devices 2 and embodying a vertical frame work 3. The concrete mixer 4 is the usual drum type mixer having the discharge opening 5 and the receiving or charging opening 6 at which is located the hopper 7. The mixer 4 is of the gear driven type and is operated by any suitable motor such as a gas engine arranged to drive the same, but not illustrated. Adapted to discharge the concrete aggregates into the hopper 7 of the mixer 4 is the loading skip 8 which is of a conventional type having its upper end reduced in size to form a charging spout 8^a adapted to enter the hopper 7 in the discharging operation during which the skip is in its uppermost dotted line position. When receiving the aggregates with which it is charged the skip 8 is ordinarily in its down position resting upon the subgrade upon which the machine travels. At its discharge upper end the skip 8 is equipped with brackets 9 for pivoting the same at the pivot point 10 to the frame work 3.

My raising and lowering mechanism comprises lifting devices including the lifting levers 11 mounted upon a cross shaft 12 carried by suitable bearings provided on the frame work 3. The levers 11 are connected by means of arms 13 with the skip 8, said arms 13 being pivotally attached at corresponding ends with the outer corresponding ends of the levers 11 by means of a cross shaft or pintle pivot member 14. By using said pivot member 14 as a common pivot between the part of levers 11 and the

part of arms 13 "side sway when on a subgrade that is crowned is resisted."

The levers 11 are equipped at their inner ends which are fixed to the shaft 12, with elliptical gear segments 15 suitably toothed so as to mesh with elliptical worm gears 16 eccentrically mounted upon a cross shaft 17 carried in suitable bearings upon the frame of the machine. The gear segments 15 are preferably cast integral with the levers 11 though not necessarily so.

One of the worm gears 16 is operated by means of a driving worm 18 mounted in the gear casing 19 and in this manner the said worm gear and its companion worm gear are simultaneously driven, the two being fixed to the shaft 17 by any suitable means such as keys.

For operation of the driving worm 18 I employ a drive shaft 20 which may be actuated by being geared to one of the gear rings 4^a of the mixing drum 4, as by means of the gear shaft 21 and gear 22 thereon in meshed relation with said ring gear 4^a. Intermediate the shaft 21 and drive shaft 20 I employ an hydraulic transmission mechanism of the type known as the oil gear, the details of construction of which are not shown but will be understood by those versed in the particular art. The oil gear hydraulic transmission generally designated at 23 may be of the types shown by United States Patents #1,489,586 issued March 4th, 1924, and #1,558,003, issued October 20th, 1925. The said transmission 23 is a combined high pressure oil pump and oil motor, self contained and in one casing and driven from the shaft 21 aforesaid. The transmission unit is a very flexible one for the purposes of my invention affording a variable and reverse speed mechanism utilized to considerable advantage as will be later seen. Said transmission 23 is equipped with a direction speed and reverse control member 24 operable by a control lever 25 which has an off standing crank arm 26.

By moving the control lever 25 to the right, as seen in Figure 1, the member 24 is operated to cause action of the transmission 23 for driving of the worm 18 at relatively low speed, said worm in turn operating the worm gears 16 and the elliptical segments 15 to thereby cause raising movement of the skip 8. Obviously, the initial raising movement of the skip 8 from the grade line involves a slow motion by reason of the cooperation of the gear elements 16 and 15, said slow motion gradually increasing as the load in the lever arm of the skip decreases, thereby during the latter part of the upward movement of the skip to its mixer charging position the speed of the movement of the skip is considerably accelerated.

By a movement of the control lever 25

to the left from the position of Figure 1, remain as the skip moves upwardly. By this action, moreover, the pin connection 33 of the trip lever 32 is moved to the lower end of the slot 34 of the trip rod 35. The skip 8 of course is moved upwards as soon as the 70 bearing pins 27 and boxes 28 reach the inner ends of the slots 29 on the arms 30. When the skip, the movement of which is accelerated during approximately the last forty degrees of its movement, has reached its upper limit 75 of movement in which it is fully discharging into the mixer 4 its abutment 37 will have struck the secondary trip lever 36 rocking the latter and causing an uplift movement on the trip rod 35 which raises the 80 arm 26 to its mid position, and sets the control member 24 of the hydraulic transmission 23 at neutral. The drive on the skip 8 is thus discontinued.

15 When the control lever 25 is in the full line position of Figure 1, the transmission 23 is neutral and no drive is transmitted by the shaft 21 to the worm gears 16 or the worm 18.

20 The automatic control means governing the action of stoppage of the skip 8 at certain times may now be set forth, for which purpose attention is especially called to the fact that the lifting arms 13 are connected 25 with the skip 8 by movable bearing means including bearing pins 27 on the sides of the skip which are mounted in blocks or boxes 28 that are adapted to slide in guide ways or slots 29 which are formed in the upper outer 30 ends of the arm 13. It will therefore be apparent that there is provided a relative movement between the lifting devices and the skip, or in other words, the connections between these parts are movable connections 35 of which special advantage is taken. From the upper outer end of one of the arms 13 leads an operating link 30 pivoted at its lower end with the arm 26 and at its upper end with one of the arms of a bell 40 crank secondary trip lever 36. The other arm of the secondary trip lever 36 is in the path of movement of an abutment 37 carried by the skip 8 near its upper end.

With the foregoing mechanism in mind 45 the complete operation of my control means may be described.

Assuming that the parts of the invention are in the positions of Figure 1 with the skip 8 supported by the subgrade at the 50 level of the latter, the control lever 25 will be thrown to the right to render the transmission 23 operative to turn the worm driven gearing at slow speed. The lifting levers 11 move pivotally upward in starting, raising the lifting arms 13 and initially causing movement of the bearing pins 27 and their bearing boxes downwards or inwards until they reach the inner ends of the guides or slots 29. The relative movement thus produced between the arms 13 and the skip 8 exerts a pull on the link 30 in a rightward direction bringing the connecting pivot point of said link with the trip lever 32 opposite the point of pivotal support 10 60 of the skip, in which position these parts

The operator may then lower the skip 8 85 by grasping and pulling the lever 25 to the left, raising the arm 26 and starting the transmission 23 to operate the worm gearing in a reverse direction and at double its previous speed of action. Obviously, the operator could not move the lever 25 upwards when the skip is in its upraised limit position because of the abutment between the parts 37 and 36. The cooperation of the parts in this connection therefore affords a 90 safety provision against unauthorized upward lifting of the skip after it has reached its discharging position.

In the downward movement of the skip, should the same for any reason strike an obstruction that would sustain its weight or stop such movement, the levers 11 and arms 13 would continue to move. The bearing boxes 28 and pins 27 would at such time be caused to slide outwardly in the slots 29 or 100 in other words, the arms 13 at their outer ends would move inwardly from and relatively to the skip 8. A pushing force would thus be exerted upon the link member 30 which would cause a contra-clockwise rocking of the primary trip lever 32 sufficiently 105 to force the trip rod 35 down and neutralize the control member 24, immediately discontinuing the drive upon the levers 11 to stop the skip before possibility of damage or 110 destruction thereof due to meeting the obstruction in its path of movement. Such automatic stopping of the descent of the skip may take place at any point in its downward travel and when so stopped the 115 operator of the machine cannot move the lever 25 except to carry the trip rod 35 in a downward direction which would set the drive mechanism immediately to operate and raise the skip from such obstruction.

As soon as this action takes place, the pivot point 31 will be caused to coincide with the pivot axis 10 and the operator then may control the skip by leftward movement of the lever 25 to cause the skip to resume its posi- 120 125 130

tion upon the grade. Whenever the transmission control member 24 is neutralized, it will be clear that the skip is held in the position which it has assumed at the time such neutralization takes place.

The subgrade may be considered to constitute an obstruction at the lower limit of movement of the skip 8 and if the operator does not previously throw the hydraulic transmission 23 out of action, the relative movement of the skip and the arms 13 will perform such function by the action of the link member 30 on the primary trip 32.

The foregoing construction and operation of parts involves no action of winding cables, drums, brakes, or even complicated gearing. The lower units will be protected by oil tight casings containing ample lubricant for complete lubrication to reduce wear. The automatic control affords safety features of pronounced advantage as it is impossible for the skip to be suddenly dropped as often now is the case. The upward and downward movements of the skip are at uniform predetermined speeds, that in raising being much lower than when lowering. It will be quite evident that the extra superstructure heretofore used for cable lifting arrangements of skips is entirely done away with.

Having thus described my invention, what I claim as new and desire to secure by Letters Patent of the United States, is:—

1. In combination, a support, a loading device mounted thereon and means for raising and lowering said device comprising a power supply source, lifting levers connected with the loading device, an hydraulic transmission unit and a mechanical transmission unit intermediate the power supply source and said lifting levers, the hydraulic transmission unit including direction reversing mechanism and the mechanical transmission unit including speed changing devices.

2. In combination, a support, a loading device mounted thereon and means for raising and lowering said device comprising a power supply source, lifting levers connected with the loading device, an hydraulic transmission unit and a mechanical transmission unit intermediate the power supply source and said lifting levers, the hydraulic transmission unit comprising a direction and speed control member for driving the lifting levers in one direction at low speed and in another direction at higher speed.

3. In combination, a support, a loading device mounted thereon and means for raising and lowering said device comprising a power supply source, lifting levers connected with the loading device, an hydraulic transmission unit and a mechanical transmission unit intermediate the power supply source and said lifting levers, the hydraulic transmission unit comprising a direction and speed control member for driv-

ing the lifting levers in one direction at low speed and in another direction at higher speed, the mechanical transmission unit including a worm driven from the hydraulic transmission unit and variable speed gearing intermediate the worm and the lifting levers.

4. In combination, a support, a loading device mounted thereon for up and down movement, lifting means, a movable connection between the lifting means and the loading device, driving mechanism for the lifting means, and instrumentalities having operative connection with said movable connection and operable by relative movement between the lifting means and the loading device for controlling the action of the driving mechanism.

5. In combination, a support, a loading device mounted thereon for up and down movement, lifting means, a movable connection between the lifting means and the loading device, driving mechanism for the lifting means, instrumentalities having operative connection with said movable connection and operable by relative movement between the lifting means and the loading device for controlling the action of the driving mechanism, and direction of movement reversing means cooperative with the driving mechanism for the purpose described.

6. In combination, a loading device, a support upon which said device is mounted, lifting devices for the loading device having movable connection therewith, driving mechanism for the lifting devices and actuating means extending between the movable connection of the lifting device and the driving mechanism for discontinuing the operation of said driving mechanism incident to relative movement between the lifting devices and the loading device.

7. In combination, a loading device, a support upon which said device is mounted, lifting devices for the loading device having movable connection therewith, driving mechanism for the lifting devices and means for discontinuing the operation of said driving mechanism incident to relative movement of the lifting devices and the loading device, said last means comprising a part operable to stop the driving mechanism when the loading device meets an obstruction in one direction of its movement, and trip devices for stopping said driving mechanism when the loading device reaches a certain limit of movement in an opposite direction.

8. In combination, a supporting frame, a loading skip pivoted at one end thereto, lifting levers movably connected at one end with the loading skip, driving mechanism operably connected with the other ends of the lifting levers to raise and lower them under control, and actuating devices extending between the lifting levers and the driv-

ing mechanism for stopping said driving mechanism at a predetermined point in its movement operable as an incident to relative movement between the lifting levers and 5 skip permitted by the movable connection therebetween.

9. In combination, a supporting frame, a loading skip pivoted at one end thereon, pivoted lifting levers, arms connected with 10 corresponding ends of the lifting levers and movably connected with the loading skip, driving mechanism connected with the opposite corresponding ends of the lifting levers, a control device operatively connected 15 between the lifting levers and the driving mechanism for stopping the operation of said driving mechanism, and trip mechanism associated with said control device and adapted to be operated by the skip at the 20 opposite extreme of its movement, to thereby discontinue the action of the driving mechanism incident to relative movement between the lifting levers and the skip permitted by the movable connection aforesaid.

25 10. In combination, a supporting frame, a loading skip pivoted at one end thereto, lifting levers, arms pivotally connecting said lifting levers with the skip, the pivotal connecting means between the arms and skip 30 comprising a movable connection permitting relative movement of said parts, driving mechanism for the lifting levers, trip means to control said driving mechanism, and an operating member intermediate the trip 35 means and said arms operable incident to relative movement between the latter parts to thereby affect operation of said control means.

40 11. In combination, a supporting frame, a loading skip pivoted at one end thereto, lifting levers, arms pivotally connecting said lifting levers with the skip, the pivotal connecting means between the arms and skip comprising a movable connection permitting 45 relative movement of said parts, driving mechanism for the lifting levers, trip means to control said driving mechanism, an operating member intermediate the trip means and said arms operable incident to 50 relative movement between the latter parts to thereby affect operation of said control means to stop the driving mechanism during 55 movement of the skip in one direction, and other trip means for actuating the control means engageable by the skip itself, to discontinue the operation of the driving mechanism to stop the movement of the skip in an opposite direction.

60 12. In combination, a supporting framework, a skip pivoted at one end thereto, lifting levers for said skip, arms connecting corresponding ends of said levers with the skip, a driving shaft, a worm shaft, a worm on the worm shaft, change speed gear- 65 ing between said worm and the other corre-

sponding ends of the lifting levers comprising elliptical gear elements in meshing relation, and an hydraulic transmission unit between the driving shaft and the worm shaft including a control member for reversing 70 the drive from the driving shaft to the worm shaft.

13. In combination, a supporting framework, a skip pivoted at one end thereto, lifting levers for said skip, arms connecting 75 corresponding ends of said levers with the skip, driving mechanism for operating the skip, a hydraulic transmission unit between the driving mechanism and the skip including a control member for reversing the 80 drive, a manual lever for operating said control member, and automatic means to operate the control member including a trip rod, secondary trip means adapted to be actuated by abutment with the skip to 85 operate said control member to stop the transmission operation of the hydraulic transmission, and other trip means connected with the control member for also stopping the operation of the hydraulic transmission, 90 and a movable connection between the skip and the lifting levers for operating said other trip means.

14. In combination, a supporting framework, a skip pivoted at one end thereto, lifting levers, arms connected with the lifting levers, movable connections between the arms and the skip permitting relative movement of the arms and skip, driving mechanism for the lifting levers to raise and 95 lower them, a control member for said driving mechanism, a trip rod connected with said control member, primary trip means including a trip lever and link connected with the arms and movable incident to relative 100 movement of the skip and arms to operate the control member to discontinue the operation of the driving mechanism.

15. In combination, a supporting framework, a skip pivoted at one end thereto, lifting levers, arms connected with the lifting levers, movable connections between the arms and the skip permitting relative movement of the arms with respect to the skip, and skip driving mechanism for the lifting 110 levers to raise and lower them, a control member for said driving mechanism, a trip rod connected with said control member, primary trip means including a trip lever and link connected with the arms and movable incident to relative movement of the skip and arms to operate the control member to discontinue the operation of the driving 115 mechanism, a manual means to actuate said control member, and a trip lever adapted to 120 be operated by the skip in its movement for also operating the aforesaid trip means to cause the control member to stop the action of the driving mechanism.

16. In combination, a support comprising 125

a frame, a loading device mounted thereon, raising and lowering means for said loading device, stop means for arresting movement of said loading device, and a shiftable connection between one of said raising and lowering means and the loading device, said stopping means being operable through said

shiftable connection when an obstacle interposed in the path of movement of said loading device is impinged in the downward movement of the loading device. 10

In testimony whereof I affix my signature.

GEORGE EVANS WEBB.
